UNITED STATES PATENT OFFICE.

ALBIN WARTH, OF STAPLETON, ASSIGNOR TO EBERHARD FABER, OF NEW YORK, N. Y.

IMPROVEMENT IN MACHINES FOR CUTTING LEAD-PENCILS.

Specification forming part of Letters Patent No. 43,267, dated June 21, 1864.

To all whom it may concern:

Be it known that I, ALBIN WARTH, of Stapleton, in the county of Richmond and State of New York, have invented a new and Improved Machine for Cutting Lead-Pencils; and I do hereby declare that the following is a full, clear, and exact description thereof, which will enable those skilled in the art to make and use the same, reference being had to the accompanying drawings, making a part of this specification, in which—

Figure 1 represents a longitudinal vertical section of my invention, the line $x x$, Fig. 2, indicating the plane of section. Fig. 2 is a plan or top view of the same. Fig. 3 is a partial section taken in the plane indicated by the line $y y$, Fig. 2. Fig. 4 is a detached plan of the carrying-roller. Fig. 5 is a detached side elevation of various carriers. Fig. 6 is a detached face view of the saw.

Similar letters of reference indicate like parts.

The final operation in the manufacture of lead-pencils is that of cutting off the ends of the same after they are otherwise completely finished. This operation, simple as it appears to be, requires great care, because it must be done after the pencils are already varnished, and without proper precaution the varnish is liable to become tarnished; and, furthermore, in cutting the ends, the edges of the wood and the ends of the lead are liable to splinter, and thereby the market value of the pencils is considerably deteriorated. For these reasons this operation requires particular care, and heretofore it has been accomplished entirely by hand-labor, at great expense and loss of time.

The object of this invention is a machine by which the operation of cutting off the ends of lead-pencils is accomplished automatically, requiring no hand-labor, except that of feeding the pencils to the machine, which can be performed by a child, and leaving both the ends of the wood and those of the lead perfectly smooth.

The construction of this machine and its operations will be readily understood from the following description.

A represents a frame, made of wood or any other suitable material, of sufficient strength and durability to support the various working parts of my machine. A hopper-box, B,

through which the lead-pencils are fed to the cutting mechanism, is secured to a cross-bar, a, which rests upon two standards, b, rising from one end of the frame A.

C is a vibrating flap, which is secured to a shaft, c, passing transversely through the hopper close under the bottom edge of one of its inclined sides. An arm, d, which is firmly secured to the shaft c, connects with a spring, d', which has a tendency to throw the flap C back in the direction of the arrow marked near it in Fig. 1, and said arm also connects by a strap, d'', with a tappet, d³, which is actuated by a series of pins, d⁴, projecting from the inner surface of a rotary disk, d⁵. By these means a vibrating motion is imparted to the flap C, whereby the pencils in the hopper-box are continually agitated and prevented from choking the throat or discharge-opening of said box. A strap, d⁶, extending from the arm d to some fixed portion of the machine, serves to take up the rebound of the flap and to ease its motions. On passing from the hopper the pencils roll between the inclined guide-plates D D', which are fastened below the discharge-opening of said hopper, as clearly shown in Fig. 1 of the drawings. The plates D' are stationary and provided with a finger, e², intended to hold the pencils down in the sockets of the carriers; but the plates D are adjustable toward and from the plates D', according to thickness of the pencils, and their lower ends form hooks e, which retain the pencils, as clearly shown in Figs. 1 and 3.

In order to compel the pencils to pass singly into the sockets of the carriers, fingers e', of india-rubber or other elastic material, are secured to the lower ends of the plates D'.

E are the carriers, which are secured to the ends of the carrying-heads E' by means of screws f. The heads E' are mounted on the shaft f', and they are so arranged that they can be adjusted farther apart or closer together to suit pencils of different lengths. In order to effect this purpose, said heads are placed on the shaft f' so that they can move on it in a longitudinal direction, and they connect by set-screws f² with a disk, f³, which is firmly keyed or otherwise fastened to the shaft f', so that by turning these set-screws the heads can be moved apart or closer together, as may be

desired. I do not wish to confine myself, however, to this particular mechanism for adjusting the heads, it being obvious that the same object can be accomplished in various different ways, either by cutting a screw-thread on the shaft f' and confining each head between two nuts, or by set-screws passing through the heads themselves.

The carriers E are provided with sockets f^4 , of different shapes, (see Fig. 5,) to receive round, hexagonal, or octagonal pencils of different thicknesses, and from one side of these sockets project lips f^6 , which are intended to knock the pencils out of the hooks e at the bottom ends of the plates D, and to cause them to drop into the sockets as the carriers successively pass under said books. On being deposited in the successive sockets of the carriers, one pencil after the other is moved through between two gages, F F', which extend from the rear cross-bar, g , of the frame A. These gages are adjusted by means of set-screws g' , so that they bear with greater or less power on the ends of the pencils protruding over the outer edges of the carriers, and one of the said carriers is made rigid by means of a Z-shaped bracket, g^2 , the point of which bears on the gage F, whereas the other gage, F', is yielding, so that it will accommodate itself to the length of different pencils. The Z-shaped bracket g^2 is adjustable backward and forward, so that more or less of the pencils can be left to protrude on the side of the rigid gage F, and the quantity to be cut off can thus be pretty evenly divided between the two sides of the carriers.

G is the belt which imparts motion to the carriers E. This belt extends from a pulley, h , on the driving-shaft h' over a pulley, h^2 , on an arbor extending across the frame A in front of the hopper-box, and over the carrying-roller, and from this pulley it extends round under the carrying-heads E', and over a pulley, h^3 , back to pulley h . The pulleys h^2 and h^3 are so situated in relation to the carrying-heads E' that by the action of the belt G motion is imparted to the carriers, and at the same time said belt presses the pencils down into the sockets of the carriers and holds them while their ends are cut off; and after the cutting operation has been accomplished said belt carries the pencils back to the chute H, from which they drop down into a box or receptacle placed there for that purpose. A slide, i , serves to shut off the discharge from the chute while the receiving-box is changed. The arbor of the roller h^5 has its bearings in boxes h^4 , to which a longitudinal sliding motion can be imparted by set screws h^5 , so that the tension of the belt G can be regulated.

The operation of cutting the pencils is effected either by the smooth-edged cutters I or by the circular saws I'. (Illustrated in Fig. 6.) Said cutters are mounted on an arbor, j , which has its bearings in suitable brackets secured to the frame A, and they (the cutters) are subjected to the action of india rubber or

other springs, j' , which keep their inner surfaces in contact with the outer surfaces of the carriers E, and they are made concave on their inner surfaces, so that their cutting-edges take effect in close proximity to the outer surfaces of the carriers, and the wood or cuttings from the pencils are prevented from getting between said outer surfaces of the carriers and the inner surfaces of the cutters. The concave form of the cutters is also essential to prevent soiling the ends of the wood with the cuttings of the lead.

The cutting-edges of the cutters, which are liable to become dull by the lead of the pencils, are continually sharpened by the action of grinding-stones or emery-wheels J, which are mounted on the ends of arbors k , that have their bearings in frames k' , to which an oscillating motion is imparted by rods k^2 , extending from eccentric wrist-pins k^3 , which project from disks secured to the ends of the shaft j' of the carrying-heads. By the oscillating motion of the frames the faces of the stones are continually drawn across the bevels at the edges of the cutters, and by this motion the operation of sharpening the cutting-edges is facilitated, and, furthermore, the faces of the grinding-stones or emery-wheels are kept level and prevented from wearing uneven. The arbors k are so arranged in the oscillating frames k' that they can assume a longitudinal sliding motion, and springs k^4 , acting on the backs of the stones or wheels J, keep the grinding-surfaces continually up to their work. A rotary motion is imparted to the grinding-wheels by means of belts k^5 , running from suitable pulleys on the driving-shaft over pulleys k^6 on the ends of the arbors k . These grinding-wheels may also be used if, instead of the cutters I, the saws I' are to be used. These saws are composed of a series of steel sectors, l , which are secured to a back of brass or other suitable material, and the faces of which are provided with radial teeth, as clearly shown in Fig. 6. By the action of the grinding-wheels on the outer surface of the saws the points are continually kept sharp, and the saws are enabled to cut without splintering the wood. The cuttings taken off from the ends of the pencils by the action of the saws or cutters drop down upon an inclined chute, K, and are deposited in front of the machine. The cut pencils are discharged from the carriers and carrying-heads by the action of fingers m , which are secured to the cross-bar g and project into grooves m' , turned in the surface of the carrying-heads to such a depth that the points of said fingers are enabled to catch below the pencils in the sockets of the carriers. On being discharged from the carrying-rollers, the pencils, by the action of the belt G, are deposited in the chute H, as previously stated. By this arrangement the operation of cutting off the ends of lead-pencils can be effected with very little hand-labor in a superior manner and without much loss of time.

What I claim as new, and desire to secure by Letters Patent, is—

1. A machine constructed, arranged, and operating substantially as herein described, for cutting off the ends of lead pencils.
2. The oscillating flap C at the bottom of the hopper-box B, constructed and operating substantially as herein described, so that the pencils in the hopper-box are agitated without having their varnished surfaces tarnished.
3. The india-rubber fingers e', arranged at the bottom of the hopper-box B, for the purpose of compelling the pencils to pass singly into the sockets of the carriers.
4. The carriers E, with sockets f⁴ and lips f⁵, in combination with hooks e at the lower ends of the plates D, constructed and operating substantially as herein described, so that

one pencil after the other is taken from the hooks e and deposited in the sockets f⁴.

5. The combination of the adjustable heads E' with the carriers E, so that said carriers can be adjusted for pencils of different lengths.

6. The concave cutter I, in combination with the springs j' and with the carriers E, constructed and operating in the manner and for the purpose substantially as herein shown and described.

7. The oscillating grinding-wheels J, applied in combination with the cutters I or saws I', in the manner and for the purpose substantially as set forth.

ALBIN WARTH.
